COMBINED NECKTIE RACK AND JEWELRY HOLDER

Adela M. Johnson, 676 E. Coolidge,
North Long Beach, Calif.

Filed Apr. 9, 1962, Ser. No. 69,631

Term of patent 3½ years

(Cl. D33—8)

FIG. 1

FIG. 2

FIG. 3

FIG. 4

FIG. 5

FIG. 6

I claim:

The ornamental design for a combined necktie rack and jewelry holder substantially as shown.
